Primary Examiner — T Chase Nelson*Assistant Examiner* — Kelly L Gross(74) *Attorney, Agent, or Firm* — Cowan, Liebowitz & Latman, P.C.; Anastasia Zhadina(57) **CLAIM**

The ornamental design for a test chamber, as shown and described.

DESCRIPTION

FIG. 1 is a front perspective view of the test chamber showing our design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,

FIG. 7 is a left side elevation view thereof.

Portions of the test chamber shown in broken lines are not part of the claimed design.

1 Claim, 7 Drawing Sheets(56)
